[57] ABSTRACT

An apparatus for dispensing substantially uniform groups of substantially identical nestable articles from the lower end of a generally vertical stack of nested articles. Clamping means are provided for holding the residuum of a stack of articles in a gravity-feed magazine while the lowermost group of articles is lowered on a support member. Means are provided for synchronizing the operation of the clamping means with the movement of the support member so that the stack is progressively lowered as successive lowermost groups are dispensed from the lower end of said stack. Means are also provided for dislodging the lowermost group from the support member after the group has been lowered far enough to become unnested from the lower end of the residuum of the stack. Further means are provided for unnesting the articles comprising a dispensed group from each other so that they are randomly scattered onto suitable receiving means such as a plate, platter, or the like.

DISPENSER FOR GROUPS OF NESTED ARTICLES

FIELD OF THE INVENTION

This invention relates to article dispensers and more particularly to such dispensers which are adapted to dispense substantially uniform groups of nestable articles from the lower end of a stack of like nested articles and wherein the stack can be replenished by adding articles to the top end of the stack.

BACKGROUND OF THE INVENTION

Some bulk commodities are measured or divided into selling units at the point of delivery to a user as opposed to being pre-packaged in selling units. For instance, in restaurants, mashed potatoes are generally divided and sold by the scoopful, pie is generally divided into sector-shape pieces, and potato chips are commonly apportioned by the handful whereas dry breakfast cereal is almost invariably available in portion-sized individual packages.

Sanitary conditions make it extremely desirable to serve foodstuffs without having them touched by servers. Although it may be expedient to serve potato chips by the handful, such non-hygienic handling tends to compromise the sanitary condition of food and, if seen by diners, concomitantly diminishes the appetites of diners.

Therefore, whenever the form of a food product lends itself to being uniformly apportioned without being contacted by servers, it becomes desirable to do so. The instant invention provides a suitable dispenser to achieve this end with respect to uniformly shaped, nested articles such as chip-type snack food articles.

U.S. Pat. No. 3,498,798 issued to Fredrick J. Baur and Harold Kenneth Hawley, Mar. 3, 1970 discloses packaged chip-type snack food articles such as potato chips, of uniform size and shape formed into a stacked array within a rigid tubular containing having a pull-tab removable end panel. Such a packaged, uniformly shaped, nested-stack, chip-type snack food is well suited for being transferred by a food handler directly from its container into the magazine of a dispenser without touching the product. Such uniformly shaped and stacked chip-type items are also amenable to being apportioned by the height of a serving. That is, groups of uniform predetermined heights will contain substantially uniform quantities of chips. Therefore, the number of chips in such groups may be varied by adjusting the height of the group.

Chip-type snack foods are generally fragile and frangible which necessitates handling them gently. Although frangible single chips may be able to withstand being dropped or thrown a considerable distance without being fractured, grouping several together in a stack tends to accentuate their susceptibility to being fractured. Whereas, a frangible chip may be dropped several inches onto a platform or support member without being fractured on impact, dropping a stack of nested, frangible chips an equal height would greatly increase the probability of fracturing one or more chips disposed at the impacting end of the stack. The greater the stack height or mass the greater the problem associated with dropping. Therefore, dispensing apparatus as well as other handling apparatus for frangible chips will desirably be addressed to lowering as opposed to dropping, moving as opposed to throwing, and so forth.

Those skilled in the vending art will be familiar with many types of dispensers having the general character of the instant invention that have been developed to overcome some of the problems to which it is addressed. Some such prior art dispensers are illustrated in U.S. Pat. No. 3,108,715 — Farnsworth issued Oct. 29, 1963; U.S. Pat. No. 2,291,187 — Johnson issued July 28, 1942; and U.S. Pat. No. 2,338,714 — Garner issued Jan. 11, 1944. However, none of these has solved all of the problems associated with vending in the manner of the present invention.

SUMMARY OF THE INVENTION

The nature and substance of the invention will be more readily appreciated after giving consideration to its major aims and purposes. The principle objects of the invention are recited in the ensuing paragraphs in order to provide a better appreciation of its important aspects prior to describing the details of a preferred embodiment in later portions of this description.

The major object of the invention is the provision of an apparatus for dispensing substantially uniform groups of substantially identical nestable articles from the lower end of a generally vertical stack of nested articles.

Another object of the invention is the provision of an apparatus for dispensing substantially uniform groups of substantially identical nestable articles so that they are randomly disposed on a suitable receiving surface as opposed to being received with the articles of the group in nested relationship.

Yet another object of the invention is the provision of an apparatus for dispensing substantially uniform groups of substantially identical nestable articles from the lower end of a generally vertical stack of nested articles without dropping the articles.

Still another object of the invention is the provision of the hereinabove described apparatus wherein the average number of articles per group is adjustable pre-determinable.

These and other objects are achieved in the present invention by providing an apparatus for dispensing substantially uniform groups of substantially identical nestable articles, which apparatus includes: a generally vertically extending gravity-feed magazine; clamping means disposed adjacent the lower end of the magazine for holding the residuum of a stack of articles in the magazine while the lowermost group of articles comprising the stack is lowered on a support member. The apparatus further comprises: means for operating the support member between an up position and a down position; means for synchronizing the operation of the clamping means with the movement of the support member so that the stack of articles is progressively lowered as successive lowermost groups of articles are dispensed from the lower end of the stack of articles in the magazine; and means for dislodging the lowermost group from the support member after the lowermost group has been lowered far enough to become un-nested from the lower end of the residuum of the stack.

BRIEF DESCRIPTION OF THE INVENTION

While the specification concludes with claims particularly pointing out and distinctly claiming the subject matter regarded as forming the present invention, it is believed the invention will be better understood from

the following description taken in connection with the accompanying drawings in which:

FIG. 1 is a fragmentary side elevational view of a dispenser, the dispenser being a preferred embodiment of the instant invention.

FIG. 2 is a fragmentary front elevational view of the preferred embodiment dispenser of FIG. 1.

FIGS. 3 through 5 are fragmentary perspective views of the dispensing mechanism of the preferred embodiment dispenser of FIG. 1 showing the operation of the dispensing mechanism during a dispensing sequence.

FIG. 6 is a fragmentary plan view of the inclined bottom panel of the discharge chute taken along line 6—6 of FIG. 1.

FIG. 7 is a fragmentary side elevation view taken along line 7—7 of FIG. 6 showing the inclined bottom panel and the pivoted strut mounted support block with a group of nested articles thereon just before the support block is passed through a shaped notch in the inclined panel. The support block is shown by dash line after passing through the shaped notch, and the nested group of articles dislodged therefrom is shown by dash line to be sliding down the inclined panel.

FIG. 8 is a fragmentary perspective view of the dispensing mechanism of an alternate embodiment of the instant invention.

FIG. 9 is a sectional view of the camming portion of a clamp operating cam of the alternate dispensing mechanism shown in FIG. 8 taken along line 9—9 thereof.

FIG. 10 is a plan view of the support operating cam of the alternate dispensing mechanism shown in FIG. 8.

DESCRIPTION OF THE PREFERRED EMBODIMENT

Referring now to FIG. 1, dispenser 20 which is the preferred embodiment of the instant invention is shown to comprise base 21, magazine 22, dispensing mechanism 23 and discharge chute 24. Briefly, operation of the dispensing mechanism 23 causes successive uniform groups 25 (FIG. 7) of nestable articles 26 to be dispensed from the bottom of the stack 27 of nested articles 26 within magazine 22 onto suitable receiving means disposed below the lower end 28 of discharge chute 24.

Base 21 functions as a means of supporting magazine 22 so that articles 26 stacked within magazine 22 can be dispensed from the lower end 29 of magazine 22 onto a plate or other suitable receiving means not integrated into dispenser 20 per se nor shown in the views thereof. Although base 21 is shown in FIGS. 1 and 2 to be suitably configured for standing dispenser 20 on a shelf or counter, suitable alternate means for supporting dispenser 20 less base 21 are considered well within the capabilities of those having ordinary skill in the art. For instance, such dispensing apparatus could be adapted for wall mounting by providing suitable attachment means for that purpose in which event most of the structure of base 21 could be eliminated.

Magazine 22, FIGS. 1 and 2, of the preferred embodiment dispenser 20, is a tubular member having a full-length vertically extending slot 30 in its front wall 31. Thus, a horizontal section through vertically extending tubular magazine 22 would have a C-shape. Although magazine 22 as depicted in FIGS. 1 and 2 has a rectangular cross section causing the C-shape to have square corners, other cross-sectional shapes could be

used without compromising the instant invention. For example, the bore of magazine 22 could be the cross sectional shape of packages in which articles to be dispensed are packaged. For instance, a stack of nested articles packed within a circular cross section tubular container such as disclosed in U.S. Pat. No. 3,498,798 issued Mar. 3, 1970 to Baur et al. could be transferred directly into a circular cross section magazine by telescoping the tubular container down through the top end of the magazine. Of course, the container would have to have first been opened and then inverted while providing temporary support for the packaged articles until they are juxtaposed the top end of the stack of articles 26 in the magazine.

Dispensing mechanism 23 of the preferred embodiment of the instant invention, best seen in FIGS. 3 through 5, comprises: operating means 35 operable between a rest and a dispensing position; clamping means 36 operable between a stack engaging position and a stack disengaging position; support and lowering means 37 operable between an up and a down position; and group height adjustment means 38. Briefly, dispensing mechanism 23 is actuated through a dispensing cycle by reciprocating the operating means 35 downwardly from its rest position to the dispensing position then upwardly to its rest position. The first downward motion of operating means 35 causes clamping means 36 to move to its stack engaging position whereby it assumes the support of articles 26 interposed therebetween and disposed thereabove, this portion of the stack of articles 26 being defined as the residuum 33. Then, the group 25 (FIG. 7) of articles 26 disposed below clamping means 36 are lowered on support and lowering means 37 until they are dislodged therefrom whereupon the group 25 of articles 26 slides down discharge chute 24 to be received therefrom. The dispensing cycle is completed by the opening of clamping means 36 after the support and lowering means 36 has been returned to its up position whereupon the residuum 33 is released. Upon being released by clamping means 36, the residuum 33 falls the height of the dispensed group 25 of articles 26 on the support and lowering means 37. The residuum 33 thereupon assumes the identity of a stack 27 of articles 26.

Operating means 35, FIGS. 1 and 2, comprises a crank 42 secured to shaft 43 which is rotatably mounted to the structure of dispenser 20 near the lower end 29 of magazine 22. Referring now to FIG. 3 wherein the structure of dispenser 20 has been omitted for clarity, shaft 43 has a radially extending pin 44 secured to it which enables shaft 43 to be biased clockwise by tension spring 45 acting on the distal end 46 of pin 44. That is, shaft 43 is biased in a manner that urges the handle 47 of crank 42 upwardly to the rest position. The radially extending pin 44 has a secondary function in combination with the operation of support and lowering means 37 as will hereinafter be delineated.

Clamping means 36, FIGS. 3 through 5, comprises arms 50, pads 51, and clamp cams 52.

The arms 50, FIG. 3, of clamping means 36 of preferred embodiment dispenser 20 are of spring material and have an L-shape. The upper end 53 of each arm 50 is secured to the sides of magazine 22 or to other suitable dispenser structure so that arms 50 are cantilevered from their secured upper ends 53. Because arms 50 are of spring material, their lower ends 54 will be biased inwardly towards each other if they are first

caused to be displaced outwardly with respect to each other. The horizontal leg 56 of each arm 50 is disposed and configured to be acted on by the camming portions 57 of clamp cams 52 upon reciprocation of shaft 43. That is, the camming portion 57 of each clamp cam 52 is configured as by beveling to cam the lower ends 54 of arms 50 outwardly with respect to each other when the camming portions 57 of clamp cams 52 are interposed between horizontal legs 56 of arms 50.

Pads 51 of clamping means 36 are of resilient material in order to enable the pads to simultaneously grip the edges of a plurality of articles interposed therebetween, FIG. 4.

A pad 51 is secured to the lower end 54 of each arm 50 so that surface 58 of one is opposite surface 58 of the other. Arms 50 and pads 51 are configured so that when no articles 26 are interposed therebetween and clamping arms 50 are not sprung outwardly by clamp cams 52, the opposed surfaces 58 are spaced less than the width of stack 27 of articles 26 to be dispensed. Therefore, the lower ends 54 of arms 50 must be displaced outwardly in order to interpose a stack 27 (shown in FIGS. 3-5 in phantom for clarity) of articles 26 therebetween whereby opposed surfaces 58 of pads 51 are biased inwardly to grip the edges of articles 26 interposed therebetween with enough force to support such articles 26 therebetween and the position of stack 27 of articles 26 disposed thereabove; that is, to support residuum 33.

Clamp cams 52, FIGS. 3-5, are secured to shaft 43 and indexed therewith to be reciprocated in spaced relation to the movement of crank 42 so that when crank 42 is at the most clockwise position of its range of travel, the rest position, the beveled camming portions 57 of the clamp cams 52 are interposed between the horizontal legs 56 of arms 50 whereby the lower ends 54 of arms 50 are spaced far enough apart, that is cammed outwardly far enough, to space opposed surfaces 58 of pads 51 from the edges of articles 26 disposed therebetween. Thus, with crank 42 in its most clockwise position, stack 27 of articles 26 is free to move vertically therebetween without being restrained by pads 51.

Support and lowering means 37, FIGS. 3-5, comprises collar 60, up-stop bar 61 having distal end 62, support member or block 63, strut 64, and spring 65.

Collar 60, rotatably mounted on shaft 43, has a circumferentially extending slot 68 disposed therein having ends 68a and 68b. When assembled on shaft 43, radially extending pin 44 extends through slot 68. This arrangement substantially precludes axial movement of collar 60 on shaft 43 while permitting crank 42 to be moved downwardly from its rest position through a predetermined arc length determined by the circumferential length of slot 68 before the movement of crank 42 causes collar 60 to be rotated. During the interval during which crank 42 is moved downwardly (counter clockwise) rotating collar 60, clamp cams 52 rotated to disengage their camming portions 57 from the horizontal legs 56 of arms 50 whereby the inwardly biased arms 50 cause opposed surfaces 58 of pads 51 to contact and engage the edges of articles 26 disposed therebetween.

Up-stop bar 61, FIG. 3, is rigidly secured to collar 60 at one end so that it extends downwardly with its distal end 62 in contact with group control cam 69 when the dispensing mechanism is at rest at depicted in FIG. 3. Thus clockwise rotation of collar 60, as positioned in

FIG. 3, is limited by distal end 62 of up-stop bar 61 contacting a point on the radially outwardly facing surface 70 of group control cam 69. This is designated the CW-MAX position of collar 60.

Support block 63 has a plan-view configuration, FIG. 6, that is smaller than the plan-view size of articles 26 so that support block 63 will pass through a shaped notch 82 in panel 76 through which articles 26 will not pass as is hereinafter amplified. Upwardly facing surface 66, FIG. 3, of support block 63 is configured to be congruent with a substantial area of the downwardly facing surface of the lowermost articles 26 in stack 27 so that the weight of stack 27 is distributed over a substantial area of the lowermost article 26 in the stack. This obviates points or areas of high stress in the lowermost article of a stack 27 of such articles resting on support block 63 that would perhaps fracture or otherwise compromise the structural integrity of frangible articles.

Strut 64 having ends 71, 72 is pivotally mounted in dispenser 20 by being secured at a point intermediate its ends 71, 72 to collar 60. Strut 64 is configured to have support block 63 rigidly secure to end 71 and one end of tension spring 65 secured to end 72. Further, strut 64 is configured and disposed so that support block 63 is movable between an up position and a down position, the up position being immediately subjacent the lower end of magazine 22 so that a generally vertically extending stack 27 of articles 26 to be dispensed from within magazine 22 will be supported thereon.

Tension spring 65 extending between end 72 of strut 64 and structure of dispenser 20, not shown in FIGS. 3 through 5, biases collar 60 to its CW-MAX position which positions support block 63 at its up position.

When support block 63 is at its up position, the lowermost article 26 disposed to be restrained by pads 51 is spaced the height of a group 25 of articles 26 above surface 66 of support block 63. Thus, the lowermost group 25 of articles 26 in stack 27 is free to be lowered on the support block 63 while residuum 33 of stack 27 is supported by clamping means 36.

The group height adjustment means 38, FIG. 3, comprises actuator 73, shaft 74, and group control cam 69 which, in combination, permit adjusting the up position of support block 63. Shaft 73 is rotatably mounted to the structure of dispenser 20 by means not shown but which will be familiar to those skilled in the art. Actuator 73 and group control cam 69 are secured to shaft 74 so that rotation of shaft 74 and group control cam 69 are concurrently effected by circularly displacing actuator 73. In this manner, the point on the perimeter 70 of group control cam 69 that will be contacted by the distal end 62 of up-stop bar 61 can be varied whereby the up position of support block 63 is adjusted. This adjusts the height of the space between pads 51 and support block 63 which essentially controls the number of uniformly thick articles 26 in a group 25 to be dispensed.

The discharge chute 24, FIGS. 1 and 2, comprises a first inclined panel 76, FIG. 1, and a second inclined panel 77, FIG. 2, obliquely oriented with respect to each other. Contiguous with the edges of the inclined panels are generally vertically extending side members 78 through 81. Thus, a group of articles 26 disengaged from support block 63, FIG. 7, slides down the first inclined panel 76 whereupon the group is caused to negotiate a descending, sharp corner in order to proceed

down the second inclined panel 77. Negotiating the corner generally causes individual articles 26 comprising group 25 to become unnested with respect to each other so that they will be scattered onto a plate or the like positioned adjacent the lower end 28 of discharge chute 24 rather than being received in a nested condition. Thus, articles 26 are scattered upon being dispensed so that they have a conventional appearance on a plate or platter or the like as opposed to being a nested group of articles.

The operation of the dispenser will be best understood by referring to FIGS. 3 through 5. At rest, crank 42 is biased upwardly, clockwise, by tension spring 45. Thus positioned, clamp cams 52 hold the opposed surfaces 58 of pads 51 away from the edges of articles 26 comprising stack 27 within dispenser 20. Also at rest, tension spring 65 biases strut 64 so that support block 63 is at its up position whereby it is supporting the stack 27 of articles 26 within dispenser 20. Referring now to FIG. 4, crank 42 has been displaced an exaggerated amount for clarity downwardly, counter clockwise, whereby the camming portions 57 of clamp cams 52 have moved downwardly from the lower ends 54 of arms 50. Thus, the inwardly biased lower ends 54 of arms 50 urge the opposed surfaces 58 of pads 51 to engage the edges of articles 26 disposed therebetween. At this time, stack 27 is essentially divided into two juxtaposed portions, the lowermost portion being a group 25 of articles 26 to be dispensed and the other portion being residuum 33. Residuum 33 needs to be independently supported while the lowermost group 25 is dispensed from dispenser 20.

Referring now to FIG. 5, crank 42 has been displaced an exaggerated amount downwardly from the position shown in FIG. 4. Also for clarity, spring 45 has been omitted from FIG. 5 due to the exaggerated displacement of crank 42. This action has caused collar 60 to be rotated counter clockwise by pin 44 acting on end 68a of slot 68 in collar 60. This in turn, has caused strut 64 to be pivoted about shaft 43 which has moved support block 63 downwardly from its up position carrying on it the lowermost group of articles 26 to be dispensed. Thus, the lowermost group of articles 26 is lowered from residuum 33 whereby the lowermost group 25 is unnested from the residuum 33. As will readily be perceived by those skilled in the dispensing art, such vertical displacement of group 25 from residuum 33 is necessary to cause unnesting, lateral displacement being precluded by the interlocking configuration of articles 26; i.e., their compound curved surfaces.

As support block 63 is lowered, FIG. 7, it passes through shaped notch 82, FIG. 6, in inclined panel 76. The edges of the lowermost articles 26 of the group 25 of articles 26 being dispensed are intercepted by the areas of inclined panel 76 contiguous to the outline 83 of notch 82. This causes the group 25 of articles 26 to be unnested and disengaged from support block 63. Then, because of the inclined disposition of panel 76, the group of articles 26 slides down the inclined panel 76 under the influence of gravity. At that point in time, as indicated by the phantom group 25a of articles 26 in FIG. 7, the articles 26 comprising group 25a are still nested with respect to each other.

When group 25a of nested articles 26 reach the lowest end of inclined panel 76, the group is forced to abruptly change its direction of travel in order to proceed down the second inclined panel 77. The abrupt

change in direction is induced by the group striking side member 80 as its drops from inclined panel 76 onto inclined panel 77. Generally, upon emerging from the lowermost end of discharge chute 24 onto suitable receiving means, not shown in the figures, the articles 26 of group 25a are unnested. It is believed that the angularly oriented members of discharge chute 24 cause the articles to become unnested as they negotiate the descending, sharp corner in chute 24. Thus, a dispensed group of articles will be scattered onto a plate or the like whereby they will have the appearance of a hand-dispensed handful of articles such as chip-type snack foods.

After a group of articles 26 have been dispensed by moving crank 42 downwardly, the dispensing cycle is completed by moving crank 42 upwardly to its rest position. After support block 63 has reached its up position, clamping means 36 are caused to release residuum 33 whereupon residuum 33 falls onto support block 63 thereby assuming the identity of stack 27 for the next dispensing cycle.

Referring back to FIGS. 1 and 2, the function of the full-length slot 30 in magazine 22 is to initially permit a stack of articles 26 to be placed directly onto support block 63 or to permit placing additional articles 26 on the top of a stack of articles magazine 22 regardless of where the top of the stack is along the height of the magazine. The full length slot enables initial loading and replenishing of stack 27 without dropping the stack or individual articles. That is, articles or pluralities of articles can be placed into dispenser 20 as opposed to being dropped thereinto; placing as opposed to dropping being the preferred mode of handling frangible articles.

Although not indicated in the figures, means for covering slot 30 in magazine 22 and the top end 32 of magazine 22 may be provided to enclose magazine 22 to improve the sanitary aspects of dispenser 20. Such slot and top covering means would of course have to be removable or displacable as by hinging in order to provide the necessary access to load or replenish the stack of articles.

An alternate dispensing mechanism 23a is depicted in FIG. 8 wherein designated members/features thereof which are identical to corresponding members/features of the preferred embodiment dispensing mechanism 23 are identically designated, and modified members have an 'a' added to their designators. Dispensing mechanism 23a lowers stack 27 of articles 26 a predetermined height during each dispensing cycle before the clamping mechanism engages residuum 33. The predetermined height is the height of a group of articles to be dispensed. Thus, dispensing mechanism 23a incrementally lowers stack 27 on support block 63 as opposed to the stack being incrementally lowered by dropping the residuum onto support block 63 as in the preferred embodiment dispenser 20 hereinbefore described.

Alternate dispensing mechanism 23a, FIG. 8, is different from dispensing mechanism 23 hereinbefore described inasmuch as: a dispensing cycle is caused by moving crank 42 to rotate shaft 43a clockwise through one revolution; the camming portions 57a of clamp cams 52a are configured to reciprocate the inwardly biased lower ends 54 of arms 50 as camming portions 57a move along a circular path as shaft 43a rotates; strut 64a is independently pivoted on shaft 90 and is in-

dependently biased upwardly by spring 65a; a support operating cam 91 is provided to reciprocate support block 63 in timed relation with the reciprocation of the lower ends 54 of arms 50 as shaft 43a rotates; and anti-CCW rotation means 100 is provided to preclude rotating shaft 43a counter clockwise.

The camming portion 57a of a clamp cam 52a is shown in sectional view, FIG. 9, to have a dwell portion 95 intermediate a beveled clamp opening portion 93 and a beveled clamp disengaging portion 94. The clamp cams 52a are secured to shaft 43a so that clockwise rotation of shaft 43a causes the lower ends 54 of clamp arms 50 to reciprocate outwardly and inwardly about their secured upper ends 53. This camming action alternately disengages and engages respectively opposed surfaces 58 from/with the edges of articles 26 disposed therebetween. The length L of dwell portion 95 enables shaft 43a to be rotated through a predetermined angle alpha while clamping pads 51 are disengaged from the edges of articles 26 disposed therebetween for a purpose to be hereinafter delineated.

Strut 64a, FIG. 8, having ends 101 and 102 is pivotally mounted with respect to the structure of the dispenser by having end 101 rigidly secured to shaft 90 which is rotatably secured to structure of the dispenser, such structure not being shown in FIG. 8 in order to clearly show the operating members of alternate dispensing mechanism 23a. Alternatively, strut 64a could have end 101 rotatably mounted on shaft 90, or strut 64a could have end 101 simply hinged to dispenser structure. End 102 of strut 64a is configured to have support block 63 rigidly secured thereto. Strut 64a is configured and disposed for support block 63 to be reciprocated along a circularly extending arc between an up position and a down position through an intermediate position and through shaped notch 82, FIG. 6, in inclined panel 76, FIG. 7.

When support block 63 is at its up position, it is juxtaposed the downwardly facing surface of the lowermost article 26 having its edges disposed in engaging relation relative to pads 51 whereby stack 27 can be wholly supported by either pads 51 or support block 63 for a purpose to be hereinafter delineated.

The distance between the up position and the intermediate position of the support block is the height of a group of articles to be dispensed. Thus, when the support block is lowered to the intermediate position while pads 51 are disengaged from stack 27, stack 27 is lowered the height of a group of articles to be dispensed. Then, engaging pads 51 with the edges of articles in stack 27 causes the residuum 33 of the stack to be independently supported while support block 63 is lowered to be down position to dispense the lowermost group of articles from the lowermost end of stack 27.

Support operating cam 91 in combination with camming portions 57a of clamp operating cams 52a provide, when properly indexed on shaft 43a, capability of reciprocating pads 51 in timed relation with the reciprocation of support block 63 so that: stack 27 is lowered the height of a group of articles to be dispensed as support block 63 moves downwardly from its up position to its intermediate position; and the residuum 33 of stack 27 is supported by pads 51 while support block 63 is lowered from the intermediate position to its down position (causing the lowermost group of articles to be dispensed) and the empty support block is returned to its up position. In this manner stack

27 is incrementally lowered without being dropped as successive groups of articles are dispensed from the lower end of stack 27.

Support operating cam 91, FIG. 10, has constant radius sectors R₁, R₂ and R₃ which determine the up, intermediate, and down positions, respectively, of support block 63 as hereinbefore delineated. The constant-radius R₁ sector functions, as shaft 43a rotates clockwise, to keep support block 63 at its up position 10 while the clamp opening portions 93, FIG. 9, of clamp cams 52a are engaged with arms 50 whereby pads 51 are disengaged from articles 26 disposed therebetween. Further clockwise rotation of shaft 43a through angle alpha causes the rise of cam 91, acting on strut 64a, to 15 lower support block 63 from its up position to its intermediate position while pads 51 are maintained open by dwell portions 95 of clamp operating cams 52a, FIG. 9. The constant-radius R₂ sector of support operating cam 91, FIG. 10, functions to maintain support block 63 at 20 its intermediate position while the clamp closing portions 94 of clamp operating cams 52a, FIG. 9, disengage arms 50 upon further clockwise rotation of shaft 43a. Still further clockwise rotation of shaft 43a causes 25 the rise (increasing radius) of sector G-H of cam 91, FIG. 10, acting on strut 64a, to move support block 63 downwardly from its intermediate position to its down position and then the fall (decreasing radius) of sector J-K of cam 91 causes support block 63 to move upwardly to its up position while clamp operating cams 30 52a remain disengaged from clamping arms 50. Referring now to FIG. 10, sectors B-C, D-E, F-G, H-J, and K-A of support operating cam 91 are constant-radius sectors which reduce the criticality of producing clamping cams 52a and support operating cam 91, and 35 of indexing them on shaft 43a.

Means for providing group height adjustment in alternate dispensing mechanism 23a are not shown in the figures because it is believed that the design of suitable means therefore is within the skill range of persons having ordinary skill in the camming art. For instance, referring to FIG. 10, cam 91 could be adapted to have interchangeable rim-sectors extending from a point within sector B-C, to a point within sector H-J that would comprise rise sectors C-D and G-H and constant-radius sector R₂. Such rim-sectors could each have a discrete R₂ radius. Thus, changing rim-sectors would permit adjusting the intermediate position of support block 63 which would, indirectly, control the average number of articles 26 in dispensed groups.

The anti-reverse rotation means 100 potato in FIG. 10 is a ratchet and pawl mechanism. However, it is not intended to limit the instant invention to the use of a ratchet and pawl anti-reverse rotation means per se.

A dispenser incorporating the alternate dispensing mechanism 23a, FIG. 8, is operated by moving crank 42 clockwise through one revolution for each group of articles to be dispensed. Except for the alternate dispensing mechanism 23a lowering stack 27 incrementally on support block 63, as opposed to incrementally dropping the stack in dispensing mechanism 23, FIGS. 3-5, articles 26 are handled identically by dispensers incorporating such different dispensing mechanisms.

While particular embodiments of the invention have 65 been illustrated and described, it will be obvious to those skilled in the art that various changes and modifications can be made without departing from the spirit and scope of the invention and it is intended to cover

in the appended claims all such changes and modifications that are within the scope of this invention.

What is claimed is:

1. An apparatus for dispensing substantially uniform groups of substantially identical nestable articles from the lower end of a substantially vertical stack of nested said articles, said stack consisting of a lowermost group and a residuum, said apparatus comprising:
- 5 a frame structure;
- a generally vertically extending magazine secured to 10 said structure for gravity feeding said stack downwardly therethrough, said magazine including means for replenishing said stack by adding articles to the top of said stack;
- 15 residuum clamping means operable between an engaging position and a non-engaging position for supporting said residuum in said magazine while at said engaging position, and for not restricting vertical movement of said stack within said magazine when at said non-engaging position;
- 20 a movable support member configured to nestingly engage the lower end of said stack when juxtaposed subjacent thereto;
- 25 operating means for moving said support member between an up position immediately subjacent the lower end of said magazine and a down position, said up position of said support member being so disposed relative to said clamping means at said engaging position when said stack rests on said support member at said up position and said clamping means is at said engaging position, the lower end of said residuum is engaged by said clamping means and said lowermost group is intermediate said residuum and said support member;
- 30 means interconnecting said clamping means and said operating means for progressively lowering said stack, and means for operating said clamping means in timed relation with moving said support member downwardly so that while moving said support member towards said down position said 35 lowermost group is lowered on said support member while said residuum is supported by said clamping means whereby said lowermost group is unnested from said residuum, said means interconnecting said clamping means and said operating means including means for maintaining said clamping means at said engaging position whenever said support member is displaced from said up position and for operating said clamping means to said non-engaging position when said support member is at 40 said up position whereby said residuum assumes the identity of said stack by being dropped the height of said group onto said support member after said support member has returned to said up position after said lowermost group has been lowered therefrom on said support member and dislodged therefrom;
- 45 means for dislodging said lowermost group from said support member while thus unnested from said residuum, said means for dislodging said lowermost group of articles from said support member comprises a first inclined panel having a shaped notch therein through which said support member passes while moving from said up position to said down 50 position, said shaped notch being smaller than the plan view of said articles being dispensed whereby the edges of the articles being lowered on the sup-

port member are intercepted by areas of the inclined panel contiguous to the shaped notch whereupon the articles are unnested from the support member and slide down the first inclined panel; and,

means for scatter dispensing a group of articles onto suitable receiving means, said means for scatter dispensing comprising a discharge chute comprising an upper chute section and a lower chute section, said upper chute section comprising said first inclined panel having side members extending upwardly from the longitudinal edges thereof, said second chute section comprising a second inclined panel having its upper end disposed subjacent the lower end of said first inclined panel and having side members extending upwardly from its longitudinal edges, said chute sections being angularly positioned relative to each other forming a sharp, descending corner at their juncture which must be negotiated by groups of articles being dispensed whereby the nested articles in such groups are induced to become unnested.

2. An apparatus for successively dispensing substantially uniform portions of nestable articles from the lowermost end of a substantially vertically extending stack of like, nested articles, said apparatus comprising lateral stack support means, a pivotally mounted strut, a support block secured to the distal end of said strut, said support block being movable between an up position and a down position by pivotally moving said strut, said support block being shaped to support said stack of nested articles when at said up position and to lower a portion of said articles as said strut is pivotally moved towards its down position, clamping means for providing temporary vertical support for the portion of the stack of nested articles disposed above the lowermost portion of said stack of articles whenever said support block is displaced from its up position, a discharge chute having an inclined member having a shaped notch therein through which said support block passes as said support block moves between said up and said down positions, and operating means adapted to cycle said support block from its up position to its down position and return it to its up position whereby a portion of nested articles is lowered on said support block from the lowermost end of said stack of articles, are subsequently disengaged from said support block as said support block moves downwardly through said shaped notch, and finally slide down said inclined member.

3. The apparatus of claim 2 wherein said discharge chute comprises two inclined chute sections angularly disposed relative to each other forming a sharp, downwardly canted corner at the juncture therebetween, said corner acting to unnest said articles comprising said group of articles sliding down said discharge chute whereby said articles are scatter dispensed from the lower end of said discharge chute onto suitable receiving means held therebelow.

4. An apparatus for dispensing substantially uniform groups of substantially identical nestable articles from the lower end of a substantially vertical stack of nested said articles, said stack consisting of a lowermost group and a residuum, said apparatus comprising:

60 a frame structure;

a generally vertically extending magazine secured to said structure for gravity feeding said stack downwardly therethrough, said magazine including

means for replenishing said stack by adding articles to the top of said stack;

residuum clamping means operable between an engaging position and a non-engaging position for supporting said residuum in said magazine while at said engaging position, and for not restricting vertical movement of said stack within said magazine when at said non-engaging position;

a movable support member configured to nestingly engage the lower end of said stack when juxtaposed subjacent thereto;

operating means for moving said support member between an up position immediately subjacent the lower end of said magazine and a down position;

means interconnecting said clamping means and said operating means for progressively lowering said stack, and means for operating said clamping means in timed relation with moving said support member downwardly so that while moving said support member towards said down position said lowermost group is lowered on said support member while said residuum is supported by said clamping means whereby said lowermost group is unnested from said residuum; and

means for dislodging said lowermost group from said support member while thus unnested from said residuum, said means comprising a first inclined panel having a shaped notch therein through which said support member passes while moving from said up position to said down position, said shaped notch being smaller than the plan view of said articles being dispensed whereby the edges of the articles being lowered on the support member are intercepted by areas of the inclined panel continuous to the shaped notch whereupon the articles are unnested from the support member and slide down the first inclined panel.

5. The apparatus of claim 4 wherein said up position of said support member is so disposed relative to said clamping means at said engaging position that when said stack rests on said support member at said up position and said clamping means is at said engaging position, the lower end of said residuum is engaged by said clamping means and said lowermost group is intermediate said residuum and said support member, said means interconnecting said clamping means and said operating means includes means for maintaining said clamping means at said engaging position whenever said support member is displaced from said up position and for operating said clamping means to said non-engaging position when said support member is at said up position whereby said residuum assumes the identity of said stack by being dropped the height of said group onto said support member after said support member has returned to said up position after said lowermost group has been lowered therefrom on said support member and dislodged therefrom.

6. The dispensing apparatus of claim 4 further comprising means for scatter dispensing a group of articles onto suitable receiving means, said means for scatter dispensing comprising a discharge chute comprising an upper chute section and a lower chute section, said upper chute section comprising said first inclined panel having side members extending upwardly from the longitudinal edges thereof, said second chute section comprising a second inclined panel having its upper end disposed subjacent the lower end of said first inclined

panel and having side members extending upwardly from its longitudinal edges, said chute sections being angularly positioned relative to each other forming a sharp, descending corner at their juncture which must be negotiated by groups of article being dispensed whereby nested articles are induced to become unnested.

7. An apparatus for dispensing substantially uniform groups of substantially identical, nestable, frangible, saddle-shape articles from the lowermost end of a substantially vertical stack of nested said articles, said stack consisting of a lowermost group and a residuum, said apparatus comprising:

a frame structure;

a generally vertically extending magazine secured to said structure for gravity feeding said stack downwardly therethrough, said magazine including means for replenishing said stack by placing without dropping, additional said articles on the top of said stack;

residuum clamping means operable between an engaging position and a non-engaging position for supporting said residuum in said magazine while at said engaging position, and for not restricting vertical movement of said stack within said magazine when at said non-engaging position;

a movable support member configured to nestingly engage the lower end of said stack when juxtaposed subjacent thereto;

operating means for moving said support member between an up position immediately subjacent the lower end of said magazine and a down position through an intermediate position, the distance between said up position and said intermediate position determining the height of said group;

means interconnecting said clamping means and said operating means for progressively lowering said stack, and means for operating said clamping means in timed relation with moving said support member, said means interconnecting said clamping means and said operating means including means for maintaining said clamping means at said non-engaging position while said support member is moved from said up position to said intermediate position to lower said stack, and means for positioning and maintaining said clamping means at said engaging position to hold said residuum while said support member is moved from said intermediate position to said down position and then moved upwardly to said up position whereby said stack is progressively lowered an incremental distance equal to the height of said group without dropping said stack, and said clamping means supports said residuum while said group is lowered therefrom on said support member and disengaged therefrom; and,

means for dislodging said lowermost group from said support member while thus disengaged from said residuum.

8. The apparatus of claim 7 wherein:

said means for replenishing said stack includes an open top end and a full length slot whereby a quantity of articles can be telescoped downwardly into the magazine through said open top end while being supported on suitable ancillary means therefore extending through said slot; and

said means for dislodging said lowermost group of articles from said support member comprises a first inclined panel having a shaped notch therein through said said support member passes while moving from said up position to said down position, said shaped notch being smaller than the plan view of said articles being dispensed whereby the edges of the articles being lowered on the support member are intercepted by areas of the inclined panel contiguous to the lineament of the shaped notch whereupon the articles are unnested from the support member and slide down the first inclined panel to a delivery point.

9. The apparatus of claim 8 further comprising means for scatter dispensing a group of articles onto suitable receiving means, said means for scatter dispensing

comprising a discharge chute comprising an upper chute section and a lower chute section, said upper chute section comprising said first inclined panel thereof, said second chute section comprising a second inclined panel having its upper end disposed subjacent the lower end of said first inclined panel and having side members extending upwardly from its longitudinal edges, said chute sections being angularly positioned relative to each other forming a sharp, descending corner at their juncture which must be negotiated by groups of articles being dispensed whereby nested articles are induced to become unnested whereby the articles of a dispensed group are scattered onto suitable receiving means upon merging from the lower end of said second chute section.

UNITED STATES PATENT OFFICE
CERTIFICATE OF CORRECTION

Patent No. 3,747,803 Dated July 24, 1973

Inventor(s) Alfred W. Zoepf & Charles R. Hood

It is certified that error appears in the above-identified patent
and that said Letters Patent are hereby corrected as shown below:

Col. 1, line 37, change "potatoe" to -- potato --.
line 52, change "qently" to -- gently --.
Col. 2, line 32, change "is" to -- in --.
Col. 5, line 67, change second "at" to -- as --.
Col. 10, line 50, change "potato" to -- illustrated --.
Col. 11, line 29, after "position", insert -- that --.
Col. 14, line 5, change "article" to -- articles --.
Col. 15, line 4, delete first "said".

Signed and sealed this 8th day of January 1974.
